CLAIM

The ornamental design for a solar powered lighting unit, as shown and described.

DESCRIPTION

FIG. 1 is a perspective views of a solar powered lighting unit; showing my new design;

FIG. 2 is a front elevational view of the lighting unit of FIG. 1;

FIG. 3 is a top plan view of the lighting unit of FIG. 1; FIG. 4 is a right side elevational view of the lighting unit of FIG. 1, it being understood that the left side elevational view is similar;

FIG. 5 is a rear elevational view of the lighting unit of FIG. 1; and,

FIG. 6 is a bottom plan view of the lighting unit of FIG. 1. The broken line showing of environmental structure in FIGS. 1, 2, 4, and 5 is for illustrative purposes only and forms no part of the claimed design. The grid system fragmentarily shown in FIGS. 1-3 extends uniformly throughout the area represented.
